UNITED STATES PATENT OFFICE.

WILBUR I. FOLLETT AND JULIUS ALSENZ, OF NEW YORK, N. Y.; SAID
ALSENZ ASSIGNOR TO SAID FOLLETT.

TIME-RECORDING APPARATUS.

No. 838,855.

Specification of Letters Patent.

Patented Dec. 18, 1906.

Application filed March 24, 1906. Serial No. 307,843.

To all whom it may concern:

Be it known that we, WILBUR I. FOLLETT, of the borough of Brooklyn, and JULIUS ALSENZ, of the borough of Bronx, city and State of New York, citizens of the United States of America, have invented certain new and useful Improved Time-Recording Apparatus, of which the following is a specification.

This invention relates to a class of time-recording apparatus especially applicable to workshop-cost keeping. It provides printing-surfaces that are brought to a common printing-line successively in different consecutive positions along such line, combined with means for taking an impression from any printing-surface when it is in position in the printing-line. The intervals between the positions of the printing-surfaces in the printing-line may represent equal periods of clock time. Therefore a movable card-holder—such, for instance, as shown in Patent No. 810,370, granted January 16, 1906, to Wilbur I. Follett—is not required. This mode of operation is best effected by disposing the printing-surfaces in a spiral line around an axis of rotation at uniform distances therefrom and providing a hammer or impression-making device equal in length to the printing-line. The printing-surfaces may be upon the faces of projections on the surface of a rotating time-controlled cylinder which at predetermined intervals of time receives or is permitted to make one step or increment of rotation, a different printing-surface being brought into the printing-line at each partial rotation. It is of course entirely feasible that such time subdivisions—that is to say, such step-by-step movements—may be separated by intervals of from one, five, ten, or fifteen minutes or other intervals, as may be desired.

In the special embodiment of the invention herein disclosed the apparatus is depicted as organized for step-by-step movements separated by intervals of fifteen minutes, thus subdividing the hour into quarters.

In order that the apparatus may be constructed without the necessity of reverse movement of any part to bring it into position for the opening hour of a shop, we employ, as above stated, a hammer whose impression-making surface is coextensive with the line of print, and for the same reason the step-by-step rotatable member carrying

the spirally-arranged printing-surfaces is 55 equipped for making impressions for a period of twelve hours, so that by its mere continuous rotation in the same direction all parts come into operative position, so that after the shutting down of the shop on one evening 60 continued rotation of the apparatus brings it into effective or operative position for the hour of the shop opening on the following day. Thus in the particular embodiment of the invention disclosed herein it is designed 65 that there shall be forty-eight spirally-arranged printing-surfaces representing twelve hours, the spaces between which represent intervals of fifteen minutes.

In the accompanying drawings, Figure 1 is 70 a front elevation; Fig. 2, an elevation of the left-hand side of the machine; Fig. 3, a top view; Fig. 4, a cross-section on the line 4-4 of Fig. 1; Fig. 5, an elevation of the right-hand side of the machine; Fig. 6, a detail 75 view in elevation, indicating the hammer, operating-lever, and hammer-tripping devices in normal position; Fig. 7, a like view showing the operating-lever depressed and the hammer tripped, and Fig. 8 a detail view 80 showing the cylinder and the spirally-arranged printing-surfaces thereon.

The frame of the machine comprises, primarily, a base *a* and upper plate *b*, and above the latter a clock-supporting platform *c*, 85 these parts being spaced and supported by appropriate columns. Mounted in bearings in plates *a* *b* is a vertically-disposed cylinder *d*, the periphery of which carries projections, in this instance forty-eight in number, 90 extending around it in a helix or spiral line from the upper to the lower end, Fig. 8. The final projection *e* at the bottom of the cylinder is not in line vertically with the first projection *f* at the top, but the two are spaced circumferentially of the cylinder in the same manner as all the other projections.

The cylinder is to be driven by any appropriate motor, an ordinary spring-drum being shown. Its gear *g'* meshes with pinion *g*² on horizontal shaft *g*³, having a bevel-gear *g*⁴ meshing with a corresponding double gear *g*⁵ on the shaft of the cylinder *d*. At the base of the cylinder there is a concentric gear *h*, meshing with a pinion *h'* on a short vertical shaft *h*², 105 which carries a larger gear *h*³, meshing with a pinion *h*⁴ on a vertical shaft *h*⁵, extending upwardly into proximity to the clock-platform.

and having upon its end a bevel-gear h^6 , meshing with bevel-gear h^7 on a short horizontal shaft which carries an escapement-disk i . The clock-train is not shown, but the 5 minute-shaft thereof is indicated at j and carries a four-toothed cam j' , upon the periphery of which bears a pin projecting laterally from a vertically-disposed escapement-lever j^2 , pivoted at j^3 and having applied to 10 it a spring j^4 , whose reaction tends to keep its upper end in engagement with the cam-wheel. Its lower end overlaps the escapement-disk i and is formed with a projection i' , extending toward the face of the disk and 15 into the path of pins i^2 i^3 , projecting therefrom in close proximity to each other and arranged at different distances from the axis of the disk. This device operates to permit the cylinder d to advance under the stress of its 20 motor one step each fifteen minutes to bring successively into the vertical printing-line the printing-surfaces of the several projections on the cylinder. The operation is as 25 follows: The cam-wheel on the minute-wheel shaft moving in the direction of the arrow rocks the lower end of the lever j^2 toward the axis of the escapement-lever and carries the projection i' out of the path of pin i^3 , permitting a very slight movement of the escapement-disk 30 until it is arrested, when its pin i^2 catches upon the projection i' . When the point or "rise" of the cam-surface of wheel j' passes out of engagement with lever j^2 , the latter moves away from the axis of the disk and out 35 of engagement with the pin i^2 , permitting the escapement-disk to complete its revolution. The driving-gears are so proportioned that this permits the cylinder to advance one step to bring a new printing projection into the 40 printing-line. The slight movement of the disk when the pin i^2 passes out of engagement with the end of lever j^2 tends to permit a very slight movement of the printing-surface then in line of printing. The movement is, however, practically taken up in the 45 gearing, so that there is no observable lack of alinement of the printing-surface in the printing-line.

The hammer k is carried by a vertical rock-shaft k' , to which is applied a coiled spring k^3 , the reaction of which tends constantly to throw the hammer to the printing plane. This hammer is coextensive in length with the cylinder d and will therefore, when 55 thrown into operation, take an impression from that one of the printing-surfaces upon the cylinder which is then in its position in the printing-line.

m represents a vertically-disposed card-holder for the reception of a workman's card upon which an impression is to be made.

n n' are ribbon-bobbins from one to the other of which a ribbon n^2 , Fig. 4, is wound, the ribbon being in width equal to the length 65 of the cylinder. Each time the hammer is

actuated, as presently described, a spring-pressed pull-pawl o , carried thereby, acts, on return of the hammer to normal position, upon a ratchet-wheel o' on the axis of the ribbon-bobbin n to effect feed of the ribbon. 70 Any appropriate ribbon mechanism may be employed. That shown is suitable for the purpose. The bobbin n' , Fig. 2, is provided with a knob or handle n^3 , by which the ribbon may be back wound. The hammer is held in normal retracted position by a pivoted latch p , that engages a projection p' , extending laterally from a collar on the rock-shaft k' of the hammer. The operating-lever q , pivoted at q' , has an upwardly-extending part q^2 , overlying the rear end of the pivoted latch. When, therefore, the operating-lever is depressed, the latch p is disengaged from projection p' , tripping the hammer, which is thrown to the printing plane by its spring k^3 . Applied to the operating-lever is a coiled spring r , attached at its upper end to a projection extending from an adjustable collar r' on one of the vertical frame-posts. This spring is of greater strength than the hammer-operating spring k^3 , and when the operating-lever is released after an impression has been taken it rises under the influence of the spring r , and a cam-surface q^4 , carried by the lever, acts upon the projection p' on the rock-shaft of the hammer, and so effects retraction of the hammer to normal position, when it is automatically reengaged by its retaining and tripping latch p . 85

The characters upon the printing-surfaces of the spirally - arranged projection on the cylinder may vary according to the system of time or cost keeping to be employed. For instance, if the workmen's cards are printed upon equally-spaced lines with indications of the actual clock time—that is to say, an indication of the hours and subdivisions of the hour into fifteen minutes, as "7.00," "7.15," "7.30," "7.45," "8.00," &c.—and these indications be spaced correspondingly with the vertical spacing of the projections upon the cylinder such projections may merely have any arbitrary character engraved thereupon—as, for instance, an arrow-head, a dot, or any desired mark. If the workmen's cards 115 be printed in spaced lines with figures representing elapsed time, the printing - surfaces may also be engraved with any arbitrary mark. If the workmen's cards be blank, the printing - surfaces may be consecutively engraved with numerals from "0" to "48" and each successive impression of a numeral would indicate an interval of fifteen minutes, and each numeral printed shows the numbers of fifteen-minute intervals of time that have 120 elapsed from the opening of the shop. The drawings show the printing-surface engraved as last described and also the way of eliminating the noon recess from the record on the card, consisting in providing those surfaces 130

corresponding with the time of the noon recess with some arbitrary mark or arranging that such surfaces shall not print at all. Thus in Fig. 1 the surface bearing the numeral "20" is followed by two surfaces, one having a dash and the other a cross, after which the consecutive numbering of the surfaces continues—"21," "22," &c. In such case there may be but forty-six (46) printing-surfaces, impressions from which indicate time—*i. e.*, from "0" to "45," inclusive—the two other surfaces, making the total up to forty-eight, (48), being eliminated in the printing operation. The printing-surfaces may be engraved with actual clock time representing successively intervals of fifteen minutes, or they may be engraved to represent elapsed time from the opening of the shop, so that the impression, from any surface gives in figures the time that has elapsed from the opening of the shop up to the time of taking the impression, subject to a variation of fifteen minutes or less with the particular form of apparatus illustrated.

25 An apparatus such as has been described is characterized by the utmost simplicity of structure. Its cost of manufacture is very small as compared with other apparatus designed to accomplish similar ends, and being 30 simple and solid in structure it is not liable to become deranged or inoperative.

It is apparent that when the hammer is tripped the impression will be taken from that surface only which is standing in the 35 printing-line and that without special provision there will be no impression made upon the card from adjoining printing-surfaces.

It will be observed that the record is for a single day and that the card-holder is always 40 stationary or immovable.

We claim as our invention—

1. Time-recording apparatus comprising a series of printing-surfaces disposed spirally about an axis of rotation and at uniform distances therefrom, time-controlled means for effecting step-by-step rotation thereof continuously in the same direction at intervals of time corresponding with equal subdivisions of an hour to successively bring the 45 printing-surfaces to a printing-line consecutively in different positions along the line, an impression device coextensive in length with the line of print and adapted to effect an impression from any printing-surface when it is in its position in the printing-line and a card-holder immovable at all times and adapted for the reception of individual workmen's day-cards upon which such impressions are made.

60 2. Time-recording apparatus comprising a series of printing-surfaces disposed spirally about an axis of rotation, time-controlled means whereby such series of printing-surfaces may be rotated step by step about such 65 axis continuously in the same direction such

steps corresponding with predetermined intervals of time representing equal subdivisions of an hour, whereby the several surfaces are successively brought to a printing-line consecutively at different points in said 70 line, an impression-hammer coextensive in length with the line of print, means for at will actuating it to take an impression from any surface that may be at the printing-line and a card-holder immovable at all times and 75 adapted for the reception of individual workmen's day-cards upon which such impressions are made.

3. A time-recording apparatus comprising a series of printing-surfaces disposed spirally about an axis of rotation and having consecutive numerals, the successive numerals corresponding with successive intervals of time representing equal subdivisions of a work period of a day, time-controlled means 80 for rotating such series of impression-surfaces step by step continuously in the same direction at uniform intervals of time to bring them successively to the printing-line consecutively at different points in such line, 85 an impression device coextensive in length with the line of print for taking an impression from any printing-surface when in its position in the printing-line and a card-holder immovable at all times and adapted for the 90 reception of individual workmen's day-cards upon which such impressions are made.

4. A time-recording apparatus comprising the combination of a series of printing-surfaces disposed spirally about an axis of rotation and bearing respectively time-indicating characters, time-controlled means for rotating such series of printing-surfaces step by step at uniform intervals of time continuously in the same direction and corresponding 100 with equal subdivisions of an hour, to bring them successively to a printing-line consecutively at different points therein, the characters upon the printing-surface being such as to coöperatively effect impressions 105 indicating time, an impression device coextensive in length with the line of print, for taking an impression from any one of the printing-surfaces that may be at the printing-line and a card-holder immovable at all 110 times and adapted for the reception of individual workmen's day-cards upon which such impressions are made.

5. Time-recording apparatus comprising a series of printing-surfaces arranged consecutively at successively uniformly increasing distance from a line of print and in a space equal in length to the line of print, time-controlled means acting to move the series of printing-surfaces step by step corresponding 120 with predetermined equal intervals of time and continuously in the same direction to successively bring them, one at each such step, to the line of print consecutively at different points therein, an impression de- 125 130

vice coextensive in length with the line of print for effecting an impression from any printing-surface when in position in the printing-line and a card-holder immovable at all times and adapted for the reception of individual workmen's day-cards upon which such impressions are made.

In testimony whereof we have hereunto subscribed our names.
